THREAD CUTTER AND CLAMP FOR SHUTTLES

Filed March 4, 1931

UNITED STATES PATENT OFFICE

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

THREAD CUTTER AND CLAMP FOR SHUTTLES

Application filed March 4, 1931. Serial No. 520,044.

This invention relates to improvements in thread cutters for the outgoing bobbin of weft replenishing looms and it is the general object of the invention to provide a cutter with 5 means which will insure the severing of the thread adjacent the shuttle eye.

At the time of replenishment in an automatic loom it is desirable to cut the end extending from the outgoing bobbin at a point 10 adjacent the eye so that said end may be withdrawn by its bobbin at the time of transfer without requiring additional devices. It is an important object of my present invention 15 to provide a shuttle with one of a pair of co-acting thread parters the other of which may be mounted independently of the shuttle and brought into action by forward movement of the shuttle. The member independent of the shuttle may have a sliding movement along 20 a hard shuttle carried surface over which the weft extends, the effect of which is to produce a tension in the weft which, in addition to the pinching action between the members, will insure thread parting.

It is a further object of the present invention 25 to provide a clamp closely adjacent the cutting members so that the tensional strain placed on the weft end may not extend back to the selvage but be limited to that part of 30 the thread extending between the cutters and the clamp.

It is another object of the present invention 35 to provide a clamping element sufficiently resilient to hold the thread against movement across the shuttle carried surface, the clamping element being soft enough to hold the weft without parting it. In the practical embodiment of my invention there will be 40 two clamping surfaces and two parting surfaces, one of each being carried by the shuttle, and for purposes of convenience the clamping and parting surfaces on the shuttle are made part of the same instrumentality, 45 although this is not essential.

With these and other objects in view which 50 will appear as the description proceeds, my invention resides in the combination and arrangement of parts hereinafter described and set forth in the claims.

In the accompanying drawing, wherein a

convenient embodiment of my invention is set forth,

Fig. 1 is a top plan view of a shuttle and thread parting and clamping mechanism made according to my present invention, 55

Fig. 2 is a side elevation taken in the direction of arrow 2, Fig. 1,

Fig. 3 is a vertical detailed section taken on line 3—3 of Fig. 1, and

Fig. 4 is a view similar to a portion of Fig. 60 1 but showing the parts in a different position.

Referring to the drawing, I have shown a shuttle S having mounted therein a bobbin B and having a shuttle eye E through which the 65 weft W extends. A side delivery eye 10 communicates with the thread passage 11 and is the outlet through which the weft is led from the bobbin chamber. When the shuttle is in the magazine side of the loom the weft will 70 extend to the left toward the adjacent selvage 12. The shuttle may be provided with a thread groove 13 which provides a small passageway for the weft between the box front 14 and the front wall 15 of the shuttle. 75

Extending above and below both the delivery eye and the groove 13 is a plate 16 held to the shuttle in any approved manner, said plate having preferably a hard surface over which the weft extends when the shuttle is 80 on the magazine end of the loom. The plate is set forth herein as having a smooth front face, but my invention is not necessarily limited to a plate characterized by such a surface. 85

The loom frame 20 has projecting therefrom a bracket 21 on which is adjustably mounted a bed 22 and cap 23 held thereto by a screw or bolt 24. Slidably mounted in the bed and under the cap is a carrier 25 the forward end of which is upturned as at 26. A lever 27, controlled by the transfer mechanism T, is pivoted at 28 and urged by a torsion spring 29 to move in a counter-clockwise direction as viewed in Fig. 1. 95

Pivoted to the slide 25 as at 30 is a cutter arm 31 the rear end of which is reduced as at 32 to have pivotal connection with a cutting head 33 the forward end of which is bifurcated as at 34. A clamp arm 35 is pivoted as 100

at 36 to the arm 31 and carries at the rear end thereof a soft cushion 37, such as rubber. The latter is positioned for engagement with the left hand part of the plate 16, whereas the head 33 is positioned to engage the right hand part of the plate. A compression spring 38 is located between the cap and bed and acts on an offset 39 of arm 31 to hold said arm in the normal position shown in Fig. 1 against 10 a stop 40 on the slide 25. A leaf spring 41 yieldingly holds the clamp arm against stop 42 on the cutter arm.

In operation, the transferring mechanism will hold the lever 27 so that the right end 15 thereof will be forward the effect of which is to maintain the slide 25 in forward position against the action of spring 38. This relation exists until transfer is about to take place, at which time that part of the transfer mechanism in contact with the lever 27 moves 20 rearwardly and the latter is free to move about its pivot in a counter-clockwise direction as viewed in Fig. 1. This motion may be induced either by the spring 29, or in the 25 absence of the latter, by the spring 38. The carrier and its pivoted arm or lever 31 will move rearwardly during the advance movement of the shuttle by action of spring 38.

As the shuttle advances due to the action of 30 the lay the cushion 37 will engage the left hand part of the plate 16 and force the weft against it. It is to be understood that the cushion will have a sufficient vertical dimension to engage the weft even though the latter be displaced either above or below its normal position. After the thread has been clamped between the cushion and the plate the head will engage the plate to pinch the weft against the latter.

40 It is to be understood that the cushion is soft enough to withstand a relatively large compression before exerting sufficient force to move the arm 31 forwardly against the action of the stiff spring 38, and it is for this 45 reason that the rear of head 33, which may be formed as a knife edge, will be able to strike the plate. During continued forward movement of the shuttle the head will have a tendency to slide along the plate toward the 50 eye, but the frictional contact between the cushion and the plate will hold the rear end of arm 35 against substantial longitudinal movement. Because of the relation of the parts, angular movement of the lever 31 55 around its pivot 30 will carry the stud 36 forwardly and also to the right so that the knife edge of the head may remain in sliding contact with the plate sufficiently long to part the weft, as indicated in Fig. 4.

60 From the foregoing it will be seen that I have provided a simple means for clamping the weft against the front wall of the shuttle prior to the parting of the weft by the action of the shuttle and the cutter head. As a result, any strain which may be imposed upon

the weft by the sliding movement of the head will be communicated no farther than the cushion, and even though breakage should exist between the head and cushion instead of at the head, the remaining end will be so short that it can be readily withdrawn from the delivery eye either by the outgoing bobbin or on the subsequent pick of the loom. It will further be seen that the cushion is of such a nature that it is capable of a relatively 70 high degree of compression before communicating a moving force to the carrier 25 or the lever 31, and during the compression of the cushion the head is free to slide along and in contact with the plate for the purpose of 75 parting the weft. It will also be seen that the spring 35 is so placed as to be operatively related to the control lever 27 and is effective to move the latter independently of the torsion spring 29. Leaf spring 41 restores the 80 parts of normal position after the cutting is completed.

Having thus described my invention it will be seen that changes and modifications may be made therein by those skilled in the art 85 without departing from the spirit and scope of the invention and I do not wish to be limited to the details herein disclosed, but what I claim is:

1. The weft parting mechanism for a loom 90 operating with a shuttle movable forwardly and from which a weft thread extends, a pair of clamping elements one of which is carried by the shuttle, a pair of thread parting members one of which is carried by the shuttle, and means to render the clamping elements 95 operative prior to the operation of the parting members during the forward movement of the shuttle.

2. In thread parting mechanism for a loom 100 operating with a shuttle movable forwardly and from which a weft thread extends, means to clamp the weft against the shuttle as the latter moves forwardly, and means to part the weft adjacent the clamping means, both 105 of said means engaging a surface carried by the front wall of the shuttle to perform their 110 respective functions.

3. In thread parting mechanism for a loom 115 operating with a shuttle movable forwardly therein and from which a weft thread extends, means to clamp the weft against the shuttle, and means to part the weft adjacent the clamping means, the clamping and parting means being brought into action by forward movement of the shuttle, both of said 120 means engaging a surface carried by the front wall of the shuttle to perform their respective functions.

4. In thread parting mechanism for a loom 125 operating with a shuttle movable forwardly therein and from which a weft thread extends, a weft clamping means, and a cutting means, each dependent for operation upon forward movement of the shuttle, the parting 130

means to operate subsequent to the operation of the clamping means, both of said means engaging a surface carried by the front wall of the shuttle to perform their respective 5 functions.

5. In thread parting mechanism for a loom operating with a shuttle movable forwardly therein and from which a weft thread extends, a pair of weft parting members one of 10 which is carried by the front wall of the shuttle, a pair of clamping elements one of which is carried by the front wall of the shuttle, the clamping elements being between the parting members and the adjacent self- 15 vage, and means to effect operation of the clamping elements prior to operation of the parting members during forward movement of the shuttle.

6. In thread parting mechanism for a loom 20 operating with a shuttle movable forwardly therein and from which a weft thread extends, a clamping and weft parting plate carried by the shuttle, a weft parting independent of the shuttle to cooperate with the plate, and 25 a thread clamp independent of the shuttle to cooperate with the plate to clamp the weft, the parting and clamping members being dependent for operation upon forward movement of the shuttle.

30 7. In thread parting mechanism for a loom operating with a shuttle movable forwardly therein and from which a weft thread extends, a clamping and weft parting plate carried by the shuttle, a weft parting independent 35 of the shuttle to cooperate with the plate, and a thread clamp independent of the shuttle to cooperate with the plate to clamp the weft, the parting and clamping members being dependent for operation upon forward movement 40 of the shuttle, the clamping means operating prior to the parting means and during operating of the latter.

8. In thread parting mechanism for a loom operating with a shuttle movable forwardly 45 therein and from which a weft thread extends, a weft delivery eye carried by the shuttle, a weft parting and clamping member carried by the shuttle adjacent the delivery eye, a thread clamping element to cooperate with the member to clamp the weft 50 against the latter, and a thread parter to engage the member between the clamp and the eye, the parter being dependent for its operation upon the forward movement of the 55 shuttle.

9. In thread parting mechanism for a loom operating with a shuttle movable forwardly therein and from which a weft thread extends, means to hold a portion of the weft 60 against the shuttle to prevent said weft from moving longitudinally of the shuttle, and a weft parter slidable along the shuttle relatively to the holding means to cut the weft.

10. In thread parting mechanism for a 65 loom operating with a shuttle movable for-

wardly and from which a weft thread extends, means to hold a portion of the weft against the shuttle to prevent said weft from moving longitudinally of the shuttle, and a weft parter slidable along the shuttle away 70 from the holding means to cut the weft.

11. In thread parting mechanism for a loom operating with a shuttle movable forwardly and from which a weft thread extends, two separate devices to force the weft 75 against the shuttle, one of said devices maintaining its longitudinal position unmoved with respect to the shuttle and the other device sliding longitudinally of the shuttle during forward movement of the latter, the 80 second named device parting the weft.

12. In thread parting mechanism for a loom operating with a shuttle movable forwardly and from which a weft thread extends, a side slipping weft parter to slide 85 along a shuttle carrier surface in engagement with the weft, and means to confine the strain on the weft incident to the side slipping member to a portion of the weft extending along the shuttle. 90

13. In thread parting mechanism for a loom operating with a shuttle movable forwardly and from which a weft thread extends, means to subject the weft to a breaking strain by placing said weft under tension, and means to confine the tensional strain to a portion of the weft extending 95 along the shuttle.

14. In thread parting mechanism for a loom operating with a shuttle movable forwardly and from which a weft thread extends, means cooperating with the shuttle to subject the weft to a breaking strain by placing said weft under tension, and means 100 cooperating with the shuttle to confine the tensional strain to a portion of the weft adjacent the point at which the tensional strain is applied. 105

15. In thread parting mechanism for a loom operating with a shuttle movable forwardly and from which a weft thread extends, means to subject the weft to a breaking strain by placing said weft under tension, and means to confine the tensional strain to a portion of the weft at a point between the 110 ends of the shuttle. 115

16. In thread parting mechanism for a loom operating with a shuttle movable forwardly and from which a weft thread extends, a combined thread cutter and weft 120 parter dependent upon the forward movement of the shuttle and acting first to clamp the weft against the shuttle and to thereafter part the weft.

17. In thread parting mechanism for a 125 loom operating with a shuttle movable forwardly and from which a weft thread extends, a combined thread cutter and weft parter dependent upon the forward movement of the shuttle and acting first to clamp 130

the weft against the shuttle and to thereafter part the weft, and a resilient mounting for said combined clamp and parter movable forwardly under a force derived from the advancing shuttle.

18. In thread parting mechanism for a loom operating with a shuttle movable forwardly and from which a weft thread extends, weft clamping means, a weft parter, means to bring the clamping means and parter into operation successively during forward movement of the shuttle by a force derived from the shuttle, the clamping means and parter being movable relatively to each other.

19. In thread parting mechanism for a loom operating with a shuttle movable forwardly and from which a weft thread extends, weft clamping means, a weft parter, means to bring the clamping means and parter into operation successively during forward movement of the shuttle by a force derived from the shuttle, the clamping means and parter being movable relatively to each other, and a common yielding support to hold said clamping means and parter in shuttle engaging position.

In testimony whereof I have hereunto affixed my signature.

OSCAR V. PAYNE.
